US0D1052245S

(12) **United States Design Patent** (10) Patent No.: **US D1,052,245 S**
Le et al. (45) Date of Patent: ** Nov. 26, 2024

(54) **FOOTWEAR**

- (71) Applicant: **adidas AG**, Herzogenaurach (DE)
- (72) Inventors: **Tru Le**, Herzogenaurach (DE); **Amir Fathi**, Herzogenaurach (DE); **Chris Holmes**, Herzogenaurach (DE); **Andreas Seefried**, Herzogenaurach (DE)
- (73) Assignee: **adidas AG**, Herzogenaurach (DE)
- (**) Term: **15 Years**
- (21) Appl. No.: **29/800,246**
- (22) Filed: **Jul. 20, 2021**

Related U.S. Application Data

- (63) Continuation of application No. 29/706,274, filed on Sep. 19, 2019, now Pat. No. Des. 928,479.

(30) **Foreign Application Priority Data**

(57) **CLAIM**

The ornamental design for a footwear as shown and described.

DESCRIPTION

FIG. 1 is a side view of a footwear.

FIG. 2 is a perspective view of the footwear of FIG. 1.

FIG. 3 is another perspective view of the footwear of FIG. 1.

FIG. 4 is another side view of the footwear of FIG. 1.

FIG. 5 is another perspective view of the footwear of FIG. 1.

FIG. 6 is another perspective view of the footwear of FIG. 1.

FIG. 7 is a front view of the footwear of FIG. 1.

FIG. 8 is a rear view of the footwear of FIG. 1.

FIG. 9 is a top view of the footwear of FIG. 1; and,

FIG. 10 is a bottom view of the footwear of FIG. 1.

1 Claim, 10 Drawing Sheets
